UNITED STATES PATENT OFFICE.

WILLIAM P. WIEMANN, OF PITTSBURGH, PENNSYLVANIA.

MANUFACTURE OF ICE.

1,232,146.

Specification of Letters Patent.

Patented July 3, 1917.

Application filed April 18, 1917. Serial No. 163,078.

To all whom it may concern:

Be it known that I, WILLIAM P. WIEMANN, a citizen of the United States, and a resident of Pittsburgh, in the county of Allegheny and State of Pennsylvania, have invented a new and useful Improvement in Manufacture of Ice; and I do hereby declare the following to be a full, clear, and exact description thereof.

10 My invention relates to the manufacture of ice, and has special reference to devices for the forming of ice in the usual cans from water placed therein.

15 The object of my invention is to provide a cheap, simple and efficient water agitating device which can be connected to such can in such a way so as to be readily and conveniently attached to and detached therefrom, and one which will so agitate the 20 water contained in such can to form pure clear ice therein.

To these ends my invention consists, generally stated, in the novel arrangement, construction and combination of parts which 25 will be hereinafter more specifically set forth and described, and particularly pointed out in the claims.

To enable others skilled in the art to which my invention appertains to construct 30 and use my improved device for the manufacture of ice, I will describe the same more fully, referring to the accompanying drawing, in which—

Figure 1 is a sectional view showing the 35 upper portion of an ordinary ice manufacturing can, having my improved device attached thereto, and with the parts of the cylinder in their normal or raised positions;

Fig. 2 is an enlarged sectional view of the 40 cylinder showing the parts in their lowered position; and

Fig. 3 is a top plan view of the cylinder and showing its connection with the can.

Like symbols of reference herein indicate 45 like parts in each of the figures of the drawing.

As illustrated in the drawing 1 is the ordinary approved form of ice can, into which the water 2 for making the ice is placed, and 50 such water extends substantially up to the dotted line 3, in such can.

At the upper portion of the can 1 and within the same is the agitator 4, which is hung from the upper edge 1' of such can, 55 and is formed of an operating cylinder 5, connected to said edge as hereinafter de-

scribed. This cylinder has the upper and lower heads 5' and 5" on each end of the same, and the lower has a curved pipe 6 leading therefrom, so as to be positioned centrally and vertically within the water in said can and at the upper portion of the same for the purposes hereinafter described.

Within the cylinder 5 is a piston 7, and within the center of the piston and extending through the same into the cylinder is the pin 8. The upper cylinder head 5' has an enlarged portion 9 extending into the cylinder, and within such head and portion are the air admission and exhaust ports 10 and 11 respectively, such admission port having a flexible pipe 12 connected thereto and leading from any suitable air pressure supply. Within the admission port 10 is an inlet valve 13, which is adapted to be seated against a seat 14 in the head 5', and is provided with a stem 15 extending through said head into the cylinder. On the inner face of the enlarged portion 9 of the head 5' and around the exhaust port 11 is the 75 packing ring 16 for forming a seat for the lever valve 17, which is positioned under the said head and is loosely supported by means of the pins 18 passing through one end of the same and secured in the enlarged portion 9.

Within the cylinder 5 is an extension spring 20, which is of spiral form in helical coils 20', and has the coil at one end secured within the head 5" as at 21, while the coil at the other end is secured in the piston 7, as at 22. One of the coils 21 is off-set or projected inwardly as at 20" for the purposes hereinafter described.

The cylinder 5 is provided with a hook 23, which extends down from the upper head 5' and is adapted to fit over the upper edge 1' of the can 1 and against the band 1" secured exteriorly to the can at such edge, to thereby suspend such cylinder and the pipe 6 forming the agitator 4 in such can. The lower end of such pipe 6 has a nozzle 24 attached thereto, and having within the same a partition 25, within which and around the same are a series of spiral shaped grooves 26 to give the water discharged back into the can from the cylinder 5, through said pipe and nozzle, a circular motion, for the purposes hereinafter described.

In the use of my improved agitating device for making ice, the water 2 to be frozen

having been placed in the can 1 up to the line 3, and the agitator 4 placed in position in such can, and as the ports of the agitator when not operating, as was shown in Fig. 5 1, with the piston 7 and valves 13 and 17 held in their raised positions by the spring 20, with the valve 13 opened and valve 17 closed, so all that is then necessary is to admit air under pressure through the pipe 12 10 and into the admission port 10. This will allow the air to pass into the cylinder 5 around the valve 13 through the port 10, and hold the lever valve 17 against its seat 16, while the pressure of such air in such 15 cylinder forces the piston 7 down against the tension of the spring 20, so that at the end of the down stroke of said piston, the inwardly projecting portion 20" on the spring 20 will come in contact with the lever valve 20 17 and force it from its seat 16 covering the exhaust port 11. This will allow the valve 17 to drop down to its open position, thereby permitting it to move away from the stem 15 on the valve 13 and enable such 25 valve to drop down on to its seat 14 to shut off the air, and with the release or shutting off of the air, the spring 20 will cause the upward movement of the piston 7 to its raised position. During the upward movement of the piston 7, the air in the cylinder 30 5 passes out through the exhaust port 11 and some of the water in the can 1 will be drawn through the nozzle 24 and pipe 6 into the cylinder 5, and when the piston reaches 35 the end of its up-stroke, the valve 17 will engage the stem 15 to open the valve 13 and close the exhaust port 11. Upon the downward movement or stroke of the piston 7, as just described, such water in the cylinder 5 40 will be discharged back into the can, from such cylinder through such pipe 6 and nozzle 24, and by reason of the angle of the grooves 26 in such nozzle, the circular motion imparted thereby to such water will 45 give a swirling or vortex action to such water entering the water in the can and enable it to reach the lowest part of the can in such action during the freezing of the water in the can, and these operations of discharging 50 the water back into the can are continued throughout such freezing.

It will thus be seen that the up or suction stroke, being actuated by the extension spring, will be uniform or regular, 55 while the down or water discharging stroke varies with the air pressure employed, so that if stronger agitation of the water in the can is desired, such air pressure is raised, and if less agitation is desired, the air pressure is lowered, while the air is acting only 60 on the down stroke, and the extension spring, on account of being attached to the agitator head and piston, only operates the up stroke.

The agitating device will act to cause a 65 strong downward flow of the water there-

from at the center of the can, which flow will be of sufficient force to reach the bottom of the can and agitate all the water therein, while the rotary action of the water leaving the nozzle of the device shall be only sufficient to cause a slight whirlpool or vortex action to the water in the can. 70

The suction of water from the can by the agitating device and the discharge of such water from the device back into the can are 75 each performed by different means, and the discharge of water is always controllable, while the operating air for the device will always be kept from contact with the water in the can, thereby overcoming the warming 80 effect of such air on such water and retarding the freezing of the water in the can. 85

As the air is used only on the down or discharge stroke, a maximum agitating effect is maintained in the water in the can with a 90 minimum expenditure of power, and as practical experience has shown, the time consumed in the up or suction stroke is about three times as long as the down or discharge stroke, the air is used only about one-fourth 95 of the time, so that this time varies with the air pressure, with increased air pressure shortening the discharge time, while the up or suction stroke remains the same.

It will be evident that in the use of my improved device, pure, clear ice can be made in the usual ice making cans and without any foreign matter appearing in the same, as such matter will be forced to the top of the water and ice, where it can be collected 100 and then wiped or taken off after the ice cake or plate is formed. 95

Various modifications and changes in the design, application, construction and operation of my improved device may be resorted 105 to without departing from the spirit of the invention, or sacrificing any of its advantages.

What I claim as my invention, and desire to secure by Letters Patent is:— 110

1. In a device for making ice from water, the combination with the receptacle for the water for freezing, of a water agitating device adapted to alternately draw water from said receptacle and force it back into said 115 receptacle under pressure, in a spiral form at the center of said receptacle.

2. In a device for making ice from water, the combination with the receptacle for the water for freezing, of an agitator comprising a cylinder having a piston therein, an extension spring secured to said cylinder and said piston, valve controlled inlet and outlet air ports in said cylinder, said agitator being adapted to withdraw water from said 120 receptacle and to discharge the same back into said receptacle under pressure and in a spiral. 125

3. In combination with a device for freezing ice, a water agitator comprising a cyl- 130

inder, a piston in said cylinder, valve controlled inlet and outlet air ports in the upper portion of said cylinder, an extension spring attached to said cylinder and said piston, 5 said agitator being adapted to withdraw water from said device and to force it back into said device under pressure.

4. In combination with a device for manufacturing ice, a water agitator comprising 10 a cylinder, a piston in said cylinder, an extension spring secured to said cylinder and said piston, and valved inlet and outlet ports in the upper portion of said cylinder, said inlet and outlet ports being adapted to be 15 operated by said spring.

5. In a device for making ice from water, the combination with the receptacle for the water for freezing, of a water agitator comprising a cylinder having a piston therein, 20 air inlet and outlet ports at the top of the cylinder, valves for controlling said ports, an extension spring secured to said cylinder and said piston, said spring being adapted to come in contact with said outlet valve to 25 unseat the same and seat the inlet valve at the end of the down stroke of said piston, and means on said piston for re-seating said outlet valve and opening said inlet valve at the end of the up-stroke of said piston.

30 6. In a device for making ice, the combination with a receptacle for water, of an agitating device comprising a cylinder having a piston therein, air inlet and outlet ports in the upper end of said cylinder, 35 valves for controlling said ports, an extension spring secured to said cylinder and said piston, said spring having an off-set therein adapted to unseat the outlet valve and seat the inlet valve at the termination 40 of the down stroke, and a pin centrally located on said piston for closing the outlet valve and opening the inlet valve at the termination of the up-stroke.

7. In a device for making ice, the combination with a receptacle for water, of a 45 water agitator detachably secured to said receptacle and comprising a cylinder having a piston therein, an extension spring secured to the top of said cylinder and said piston, valved inlet and outlet ports in the top of 50 said cylinder, a pipe connected to the lower end of said cylinder and positioned centrally at the top of said receptacle, said piston being adapted to be operated alternately by fluid entering said inlet port and by said 55 extension spring, said agitator being adapted to draw water from said receptacle on the upward stroke of said piston and to discharge said water, through said pipe, on the downward stroke of said piston in a spiral 60 form under pressure.

8. In a device for making ice, the combination with a receptacle for water, of a water agitator detachably secured to said receptacle and comprising a cylinder having a 65 piston therein, an extension spring secured to the top of said cylinder and said piston, valved inlet and outlet ports in the top of said cylinder, a pipe connected to the lower end of said cylinder and positioned centrally 70 at the top of said receptacle, a nozzle on said pipe having grooves therein, said piston being adapted to be operated alternately by fluid entering said inlet port and by said extension spring, said agitator being adapted 75 to draw water from said receptacle on the upward stroke of said piston and to discharge said water, through said pipe, on the downward stroke of said piston in a spiral 80 form under pressure.

In testimony whereof, I the said WILLIAM P. WIEMANN, have hereunto set my hand.

WILLIAM P. WIEMANN.
